UNITED STATES PATENT OFFICE.

CHARLES CLEVELAND McCOMBS, OF STEPHENVILLE, TEXAS.

CHECK-PROTECTOR.

1,219,336.

Specification of Letters Patent. Patented Mar. 13, 1917.

Application filed May 11, 1916. Serial No. 96,888.

To all whom it may concern:

Be it known that I, CHARLES CLEVELAND McCOMBS, a citizen of the United States of America, residing at Stephenville, in the county of Erath and State of Texas, have invented certain new and useful Improvements in Check-Protectors, of which the following is a specification, reference being had therein to the accompanying drawing.

10 This invention relates to a check protector and has for its principal object the production of a device which is so constructed as to facilitate the perforating of certain portions of a check and thereby prevent unauthorized tampering with the subject-matter 15 as appearing thereon.

Another object of this invention is the production of a check protector wherein the body is formed from a blank and is provided with a plurality of spring-like jaws being adapted to support the perforating rollers in such a manner that the check may be inserted between the jaws at various positions, thus permitting the perforating rollers 25 to engage the check at different points thereon.

Another object of this invention is the production of a check protector wherein the jaws have parallel spring tongues so as to carry the perforating rollers along the central longitudinal axis of the jaws, whereby the check being positioned between the jaws will be in the correct position to have the rollers move toward the longitudinal axis of 35 the check, while the tongues are formed so as to yield slightly when necessary, thus taking up undue pressure.

With these and other objects in view this invention consists of certain novel combinations, constructions, and arrangements of parts as will be hereinafter fully described and claimed.

In the accompanying drawing:

Figure 1 is a top plan view of the check protector, showing the same in use.

Fig. 2 is a side elevation of the check protector.

Fig. 3 is a fragmentary enlarged longitudinal section through the outer end of one jaw, showing the perforating roller in side elevation.

Fig. 4 is a plan view of the blank from which the jaws are formed.

Referring to the accompanying drawing by numerals it will be seen that the body 1 is formed from a blank sheet of material and is preferably diamond shaped as in the plan

view of the blank as shown in Fig. 4. Thus, it will be seen that the jaws 2 are tapered from the body 1 to their outer reduced ends. 60 This body 1 is bent transversely so as to cause the jaws 2 to extend substantially in parallel planes. In this manner it will be seen that a substantially U-shaped supporting body and jaws are provided so as to permit the check to be inserted therein for a considerable distance when the protector is in operation.

The outer ends of the jaws 2 are bent to provide the outer tongues 3 having apertures 4 formed therein. Adjacent these tongues 3 the jaws 2 have inwardly extending inner tongues 5 struck therefrom, these tongues 5 being bent along the lines 6. It should be noted that these lines 6 are at a spaced distance from the portions of the tongues 5 which extend directly from the jaws 2, whereby the bases of the tongues 5 will be carried normally in alinement with the jaws 2. These tongues 5 are also provided with apertures 7 so that when the tongues 3 are bent so as to extend toward each other and the inner tongues 5 are bent so as to extend toward each other, it will be seen that the apertures 4 of the outer tongues 3 will be in 85 alinement with the apertures 7 of the inner tongues 5. At this time the usual perforating rollers 8 will be positioned between each pair of jaws so as to allow the pintles 9 to fit within the apertures 4 and 7 for rotatably 90 supporting the perforating rollers 8. It is, of course, obvious that each jaw 2 is adapted to carry a perforating roller 8, as clearly shown in Fig. 2, so as to permit a check to be passed therebetween when the check protector is in use.

When this check protector is in operation it may be used upon a check as referred to herein at 10, permitting the check to extend between the slots as shown. If it is so desired the numerals designating the amount of the check may be perforated and in this operation written designating numerals may also be perforated. In the operation of perforators of this type now in use it is only possible to perforate the portions of the check adjacent the marginal edge for it is impossible to perforate an entire line as the protector is shown to be doing in Fig. 1, for in the usual style of protectors the perforating rollers extend across or transversely to the longitudinal axis of the body or the jaws. The rollers as above set forth, however, extend in the same plane as the longi-

tudinal central axis of the jaws and as a consequence when the jaws are moved to one side the rollers may engage and perforate the check as shown.

- 5 It should be noted by referring particularly to Figs. 2 and 3 that owing to the fact that the inner ends of the tongues 5 are in alinement with the body, since the side portions of the tongues 5 are cut so as to extend 10 for a distance beyond the lines 6 thereof, when undue pressure is brought to bear upon the jaws the spring tongues 5 will yield slightly as indicated in dotted lines in Figs. 2 and 3, whereby the rollers will be retained 15 in engagement with each other throughout their entire lengths, since as soon as undue strain is brought to bear upon the protector it will be taken up by the yielding of the inner spring tongues 5. If the tongues were 20 not formed in this manner but were bent downwardly adjacent the inner ends of these cut side portions then the undue pressure exerted upon the tongues would cause the outer ends of the jaws to be sprung apart, 25 and thus the rollers would not operate throughout their entire lengths. It should further be noted that if so desired the body 1 may be provided with slots 11 which not only improve the appearance of the 30 protector but also permit nails or hooks to be passed therethrough when it is desired to carry the protector upon a supporting surface, such for instance as a desk.

From the foregoing description it will be 35 seen that a very simple and efficient check protector has been produced which may be formed from a minimum number of parts at a very reduced cost thereby enabling it to be sold at such a price as to make it possible 40 for this protector to be purchased by anybody and, furthermore, owing to the fact that the perforating rollers extend along the longitudinal axis of the jaws it will be seen that checks may be perforated by moving 45 the protector longitudinally thereof, thus causing the entire line of the check to be perforated.

What is claimed is:

1. A check protector of the class described, comprising a body, jaws extending from said body at substantially parallel planes with respect to each other, and perforating rollers carried upon said jaws in alinement with each other, said rollers extending along 55 the central longitudinal axis of said jaws, whereby the protector may permit a check to be passed therebetween, at which time the protector will move longitudinally of the check so as to cause the rollers to perforate 60 the same.

2. A check protector of the class described comprising a body, substantially parallel jaws extending from said body, inwardly

extending spring tongues formed upon said jaws, perforating rollers longitudinally 65 mounted upon said tongues, said rollers extending in the same planes as the longitudinal axis of said jaws, whereby a check may be positioned between said jaws at a desired distance after which the protector may be 70 moved along the check so as to cause the perforating rollers to form a line of perforations.

3. A check protector of the class described comprising a central body, jaws formed 75 upon said body and tapering toward their outer ends, a reduced tongue formed upon the outer end of each jaw, said tongues extending toward each other, inner spring tongues struck from said jaws at distances 80 from the outer ends of said jaws, said inner spring tongues extending toward each other, the inner spring tongue upon one jaw being in alinement with the tongue formed upon the outer end of the respective jaw, perforating rollers carried by said tongues so as to abut against each other when the jaws are urged toward each other, said rollers extending in the longitudinal plane of the axis of said jaws, whereby a check may be passed 90 between said jaws to a point desired at which time the jaws may be swung toward each other so as to cause said rollers to engage the check, whereby by moving the perforator along the check a complete line of 95 perforations may be formed therein.

4. A check protector of the class described, comprising an enlarged central body, jaws extending from said body and tapering toward their outer ends, inwardly extending 100 tongues formed upon the outer ends of said jaws, inner spring tongues struck from said jaws adjacent their outer ends, said last-mentioned tongues being bent so as to have the portion thereof adjacent their bases to 105 extend normally in the same plane as said jaws, perforating rollers carried by said spring tongues, said perforating rollers extending in the plane of the central longitudinal axis of said jaws, whereby a check may be 110 passed between said jaws to a desired point at which time said jaws may be swung toward each other so as to cause said rollers to grip firmly upon the check and form a row of perforations therein as the protector is 115 moved along the check, and said last-mentioned spring tongues being adapted to yield slightly by moving outwardly when excessive pressure is brought to bear upon said jaws, whereby said rollers will be permitted 120 to remain in engagement with each other at all times.

In testimony whereof I hereunto affix my signature.

CHARLES CLEVELAND McCOMBS.
